UNITED STATES PATENT OFFICE.

WILLIAM B. McHENRY, OF GRAFTON, WEST VIRGINIA.

DRYING-KILN.

SPECIFICATION forming part of Letters Patent No. 629,202, dated July 18, 1899.

Application filed October 5, 1898. Serial No. 692,689. (No model.)

To all whom it may concern:

Be it known that I, WILLIAM B. McHENRY, of Grafton, in the county of Taylor and State of West Virginia, have invented certain new and useful Improvements in Drying-Kilns; and I hereby declare that the following is a full, clear, and exact description thereof, reference being had to the accompanying drawings, which form part of this specification.

This invention is an improvement in drying-kilns of the class which are designed to be operated continuously and wherein the material to be dried is passed gradually through the kiln from the warm to the hottest portion thereof, so as to be properly dried and baked during its passage therethrough.

The kiln is adapted for drying brick, pottery, lumber, and other materials in large quantities economically, and may be made of various dimensions, according to the material to be dried. The general construction thereof, wherein the present invention is embodied, will be clearly understood from the following description, taken in connection with the accompanying drawings, forming part of this specification.

The invention is concisely stated in the claims following the description, and without further preliminaries I will proceed to describe the construction thereof.

Referring to the accompanying drawings, Figure 1 is a longitudinal vertical section through the kiln, showing one of the drying-chambers and the heating apparatus. Fig. 2 is an end elevation thereof on line 2 2, Fig. 3. Fig. 3 is a horizontal section on line 3 3, Fig. 2. Fig. 4 is a detail transverse section on line 4 4, Fig. 1; and Fig. 5 is a detail section on line 5 5, Fig. 4.

The kiln is constructed with one or more longitudinal drying-chambers A, which are provided with suitable doors at their opposite ends and with tracks, upon which cars carrying the objects to be dried may be run through the kiln.

As shown in the drawings, the kiln is provided with four parallel drying-chambers A. Below the discharge end of each chamber A is a furnace B, provided with an ash-pit B' and with an outlet or smoke-flue b, which extends longitudinally beneath the floor of the drying-chamber to the receiving end thereof,

at which point it communicates by a lateral passage b' with a vertical smoke-flue C, which communicates at top with a common flue C', which leads to the vertical common uptake or chimney C², as shown in Fig. 2.

As indicated in Fig. 3, the two left-hand chambers A communicate with vertical flues C at the left of the kiln, while the two right-hand chambers A communicate with vertical flues C at the right of the kiln. This enables half the kiln to be operated while the other half is being cleaned or repaired, if desired, and facilitates cleaning or repairing of the kiln without entirely stopping its operation.

The walls of each furnace B are made hollow for the purpose of affording air-heating passages D, E, and F. The passages D and E are arranged one above the other in the side walls of the furnace, and the passage F is located in the top wall of the furnace. The passages F communicate with the drying-chamber A through openings f in the floor thereof, as shown, and passages E communicate with the drying-chamber through openings e in the floor thereof, and D communicates with the drying-chamber through openings d in the floor thereof. The openings d are the innermost ones, and between them and openings e and f is a large metallic plate, G, which forms part of the roof of the smoke-flue b and part of the floor of the drying-chamber. This plate being thus located near the outlet of the furnace will be subjected to the heat of the outwardly-flowing products of combustion at this point, where they will naturally be the hottest. The object of this metallic plate is to cause a rapid circulation of hot air in the drying-chamber.

This plate will be more highly heated than that in any other part of the room and will rapidly flow upward, and thus produce a natural circulation of air within the drying-chamber, which circulation will be further increased by the draft through the uptake, as hereinafter explained. The circulation of air will be increased by the inflow of heated air through the openings d, e, and f, and the whole is so arranged that, as will be obvious, too

the material to be dried will be subjected to the greatest heat and the most violent of the hot-air currents as it nears the delivery end of the kiln, which is desirable, as the drying-

rooms are made very long and the material is moved gradually therethrough, so that by the time it reaches the delivery end it has been sufficiently dried to prevent injury thereto by the greater heat and more highly heated currents of air to which it is there subjected.

The draft of the furnaces can be independently regulated by valves *c* in the flues *C*, as indicated.

The receiving end of each drying-chamber communicates with the uptake *C*², as indicated in Fig. 2, but this communication can be closed by means of a valve *H*. When the valves *H* are opened, a direct upward draft is afforded through the drying-chambers to the uptake *C*², as indicated by tailed arrows on the right-hand side of Fig. 2. Beneath the floor at the receiving end of the drying-chamber is a transverse vapor-flue *I*, which communicates with the drying-chambers through openings *i* in the floor thereof, as indicated in Figs. 2 and 3, and also communicates with the vertical flues *J* beside smoke-flues *C*, and these vertical flues *J* communicate at top with the common flues *C*' and through them with the common uptake *C*², as shown. The flues *J* are also provided with cut-off valves *j*. When the valves *H* are opened, the valves *j* should be closed, and when valves *j* are opened the valves *H* should be closed, as indicated in the left-hand side of Fig. 2. Then the heated vapors in the drying-chambers instead of escaping directly upward into the uptake *C*² will be compelled to pass down through the floor into flues *I*, and thence through flues *J* and *C*' to the uptake *C*². I am thus enabled to produce either a direct upward draft through the chambers, as indicated in the right-hand side of Fig. 2, or a downdraft through the chambers, as indicated in the left-hand side of Fig. 2. The direct upward draft may be employed when the material in the kiln is perfectly "green" or very moist, as there will be more vapors generated then, and it is better to permit them to escape freely; but after the material is partially dried the downdraft might be more advantageously employed, and by so doing the heat will be economized, as it will be retained in the drying-chambers longer and only the heavier and denser portions of the vapors will escape, the lighter, hotter, and drier vapors rising to the top of the chamber and forcing down the denser moist vapors, which pass out through the flues *I*, *J*, *C*', and *C*², as indicated.

It will be observed that the products of combustion are preferably not admitted onto the material in the kiln, (although on very coarse material, if desired, they might be admitted by removing the plates *G*,) being conducted through the smoke-flues *b* under the entire length of the drying-chamber and under the floor thereof, heating the same, and as they escape through the flues *C*' *C*² they create a natural draft in the uptake and

flues sufficient to induce a very rapid circulation of air through the drying-chamber, even when the valves *H* are closed and the vapors have to pass through the bottom flues *I*.

By the improved construction of kiln above described I am enabled to dry the material very thoroughly and rapidly and to regulate the heat and temperature to which the material is subjected in the most advantageous manner; also, to operate the kiln continuously; and of course the number of drying-chambers may be increased and the proportions of the kiln be varied without departing from the scope of my invention, according to the material to be dried therein and according to the desired capacity of the kiln.

When drying bricks, the relative length of drying-chambers might be about one hundred feet, and the furnaces and air-flues would be about twenty to twenty-five feet in length, and they would be so arranged that the openings *d* would be about twenty feet from the exit of the drying-chambers.

Having thus described my invention, what I therefore claim as new, and desire to secure by Letters Patent thereon, is—

1. In a drying-kiln, the combination of the drying-chamber, a furnace for heating the same, an air-inlet at one end of said chamber, an uptake at the receiving end thereof, and smoke-flues exterior to the drying-chamber for conducting smoke to the said uptake; with a valve for establishing direct communication between the upper part of said drying-chamber and said uptake, and valved smoke-flues for establishing communication between the bottom part of said drying-chamber, and said uptake, said valved outlets for the vapors from the drying-chamber, being located at the end of the chamber opposite the air-inlet, and being adapted to be used alternately, substantially as described.

2. In a drying-kiln, the combination of the drying-chamber, a furnace for heating the same at one end thereof, heating-passages beside the furnace; an uptake at the opposite end of the chamber and a smoke-flue under the drying-chamber for conducting smoke to said uptake, a valved opening in the top of the drying-chamber, near the inlet end thereof for establishing direct communication between the upper part of said drying-chamber and said uptake, and a valved flue for establishing communication between the bottom part of said drying-chamber, and said uptake, said valved outlets for the vapors from the drying-chamber being adapted to be used alternately, substantially as described.

3. In a drying-kiln, the combination of the drying-chamber, an uptake at one end thereof, a furnace under the other end thereof, and smoke-flues under the floor of the drying-chamber for conducting the products of combustion from the furnace to the uptake; with a metallic plate forming part of the top of said flue and of the floor of the drying-chamber and located near the primary out-

let of the furnace so as to be subjected to the most intense heat therefrom, for the purpose and substantially as described.

4. In a drying-kiln, the combination of the drying-chamber, an uptake at the receiving end thereof, a furnace under the discharge end thereof, and smoke-flues under the floor of the drying-chamber for conducting the products of combustion from the furnace to the uptake; with air-heating passages in the walls of the furnace, communicating with the interior of the chamber, and a metallic plate forming part of the top of said flue and of the floor of the drying-chamber and located near the primary outlet of the furnace so as to be subjected to the most intense heat therefrom, said air-heating passages opening into said drying-chamber at opposite ends of said metallic plate, for the purpose and substantially as described.

5. In a drying-kiln, the combination of the drying-chamber, the uptake at the receiving end thereof, the vertical parallel smoke-flue and vapor-flue communicating with said uptake above the top of the drying-chamber, a valved opening in the top of the drying-chamber near the receiving end thereof, directly communicating with said uptake, and an opening in the floor of said chamber near the receiving end thereof, communicating with the lower end of said vapor-flue, and a valve in said vapor-flue, said valved opening and said vapor-flue to be used alternately, for the purpose and substantially as described.

35 6. In a drying-kiln, the combination of the drying-chamber, a furnace under the discharge end of the chamber air-heating passages in the walls of the furnace, communicating with said drying-chamber through

openings in the floor thereof, a smoke-flue underlying the floor of the drying-chamber for conducting the products of combustion from the furnaces to the smoke-flue at the discharge end of the drying-chamber, and a metallic plate forming part of the top of said horizontal smoke-flue and of the floor of the drying-chamber and located near the furnace, for the purpose and substantially as described.

7. In a drying-kiln, the combination of the drying-chamber, the uptake at the receiving end thereof, the vertical smoke-flue and vertical vapor-flue communicating with said uptake a valved opening in the top of the drying-chamber near the receiving end thereof, directly communicating with said uptake, and an opening in the floor of said chamber near the receiving end thereof, communicating with said vapor-flue, and a valve in said vapor-flue; with a furnace under the discharge end of the chamber, air-heating passages in the walls of the furnace, communicating with said drying-chamber through openings in the floor thereof, a smoke-flue underlying the floor of the drying-chamber for conducting the products of combustion from the furnace to the vertical smoke-flue, and a metallic plate forming part of the top of said horizontal smoke-flue and of the floor of the drying-chamber and located near the air-inlets, for the purpose and substantially as described.

In testimony that I claim the foregoing as my own I affix my signature in presence of two witnesses.

WILLIAM B. McHENRY.
